US00D668563S

(12) **United States Design Patent**
Isely et al.

(10) **Patent No.:** **US D668,563 S**
(45) **Date of Patent:** **** Oct. 9, 2012**

(54) **SAMPLE CHAMBER**

(75) Inventors: **Nikolas M. Isely**, Moraga, CA (US);
Jonathan K. Brown, Lake Forest, CA (US);
Marc E. Van Eden, North Tustin, CA (US)

(73) Assignee: **Zymo Research Corporation**, Irvine, CA (US)

(**) Term: **14 Years**

(21) Appl. No.: **29/387,488**

(22) Filed: **Mar. 14, 2011**

(51) **LOC (9) Cl.** 10-04

(52) **U.S. Cl.** **D10/68**

(58) **Field of Classification Search** D8/68;
173/90, 94, 122, 128, 170; 227/107, 113,
227/140, 147; 362/119

See application file for complete search history.

(57) **CLAIM**

The ornamental design for a sample chamber, as shown and described.

DESCRIPTION

FIG. 1 is a left side perspective view of my design;

FIG. 2 is a front view of my design;

FIG. 3 is a back view of my design;

FIG. 4 is a right side view of my design;

FIG. 5 is a left side view of my design;

FIG. 6 is a top view of my design; and,

FIG. 7 is a bottom view of my design.

All other surface(s) or portion(s) of my design not shown in the figures or otherwise described in the specification form no part of the claimed design.

1 Claim, 5 Drawing Sheets

FIG. 1
